PRODUCTION OF MOTOR FUEL

Harold V. Atwell, White Plains, and Malvin R. Mandelbaum, New York, N. Y., assignors to Process Management Company, Inc., New York, N. Y., a corporation of Delaware

Application January 9, 1936, Serial No. 58,270

4 Claims. (Cl. 196—9)

Our invention relates to the production of low-boiling hydrocarbon oils suitable for use as motor fuel from relatively high-boiling hydrocarbon oil and normally gaseous hydrocarbons.

5 In cracking relatively heavy oil, the products, in addition to such coke or carbon as may be formed, ordinarily comprise constituents both heavier and lighter than the original charging stock, ranging through residual oils or tars, gas 10 oils and kerosenes, gasoline and gases. The composition of the gases will vary considerably in accordance with the particular conditions of operation, but the gases ordinarily include hydrogen, methane, other paraffinic constituents, such 15 as ethane, propane and butanes, and varying amounts of olefinic constituents, such as ethylene, propylene and butylenes. It was suggested quite early in the development of the cracking art that a portion or all of these gases should 20 be re-circulated in the cracking process with the thought that by reason of some sort of mass action effect or the like, the retention of the gases in the stream would reduce the amount of gases formed. However, this result was not 25 obtained to any substantial degree. More recently, with the development of gas polymerization methods, it has been suggested that the cracking gases should be freed from hydrogen and methane and the remaining fractionated 30 gases be returned to the oil cracking operation. Under such conditions, polymerization or conversion of the olefinic constituents of the gases is actually observed to some extent but the yields obtained are susceptible to further improvement.

35 It is, therefore, an object of our invention to provide a process for the production of motor fuel by reaction between normally liquid and gaseous hydrocarbon materials that shall be more effective than the methods previously suggested, together with such additional operative 40 advantages and improvements as may herein-after be found to obtain.

It has been observed that, under elevated temperature and pressure and especially in the presence of certain catalysts, reactions between olefins and paraffins or between paraffins and other non-paraffinic constituents, or the products of decomposition thereof, may take place to a considerable extent but the extent to which these 45 reactions take place is influenced to a marked degree by the concentrations of the respective constituents. This is borne out by the fact that the removal of hydrogen and methane from cracking plant gases to be recycled in an oil cracking operation makes it possible to obtain 50

a yield of motor fuel which could not be obtained were the hydrogen and methane retained in the recycled gases.

We have observed that it is highly desirable that means should be afforded whereby normally gaseous materials of an olefinic character may be afforded an opportunity to react with or in the presence of hydrocarbon oils of paraffinic character and, conversely, whereby normally gaseous paraffins may be afforded an opportunity to react with or in the presence of hydrocarbon oil constituents of a non-paraffinic character. It may be observed at this point that the lower boiling gases are less susceptible to treatment and, as will be explained hereinbelow, 15 it is ordinarily desirable to remove methane from the paraffinic gases and sometimes ethane as well, whereas ethylene may similarly be removed from the olefinic gases before reaction.

If mixed paraffinic and olefinic gases are reacted with mixed paraffinic and non-paraffinic oils, the concentration effects tend to reduce the extent of inter-reaction and conversion taking place. Therefore, our invention contemplates segregating the paraffinic and non-paraffinic 25 constituents of hydrocarbon oil and hydrocarbon gases and effecting reaction between olefinic gases and paraffinic oil in one stage and reaction between paraffinic gases and non-paraffinic oil in a separate stage, whereby a more complete 30 degree of inter-reaction may be obtained.

We do not concern ourselves with the exact mechanism of this reaction and are content to state that reactions of this type can be effected to a worthwhile extent when beneficially influenced by concentration factors. According to the views of some investigators, alkylation takes place. Others have suggested that the energy liberated by the olefinic or unsaturated constituents causes the decomposition and resultant 40 polymerization or alkylation of the paraffinic constituents, while still other investigators have suggested that free radicals produced by the decomposition of the more easily decomposable class of constituents exert what may be generally termed "an activating effect" upon the conversion of the remaining constituents. But, in any event, it is our conception that whatever the mechanism of the reaction, it is beneficially influenced by conducting the reaction under such 45 conditions that the paraffinic or olefinic constituents of the gas in any particular reaction stage are relatively free from other gaseous constituents of the opposite type, respectively, and the individual types of constituents of the oil 50

55

are likewise free from oil constituents of the opposite type.

In order that our invention may be clearly set forth and understood, we now describe, with reference to the drawing accompanying and forming a part of this specification, various preferred forms and manners in which our invention may be practiced and embodied.

In this drawing the single figure is a more or less diagrammatical view of a system in which the process of our invention may be carried out, individual units thereof being shown in a more or less conventional manner. Referring now to this figure, a hydrocarbon oil suitable for conversion to lower boiling constituents and which may comprise a gas oil, a reduced crude or even a naphtha is delivered through a line 1 having a pump 2 to a solvent extraction unit of conventional type wherein the oil is treated with a suitable solvent to separate it into a paraffinic fraction and a non-paraffinic fraction. Various solvents, such as liquefied sulphur dioxide, furfural, dichlor diethyl ether, phenols and other solvents known in the art, may be employed for this purpose. Various specific manners of obtaining the separation into various paraffinic and non-paraffinic constituents are known in the art. In any event, a paraffinic oil fraction is removed from the unit 3 through the line 4 while a non-paraffinic fraction is removed from the unit 3 through a line 5. It will be understood that the paraffinic fraction may not be entirely free of non-paraffinic constituents and vice versa but, in any event, the separation is carried out as completely as possible under existing conditions and that, in any event, a materially greater concentration of paraffinic constituents, on the one hand, and non-paraffinic constituents, on the other, obtains in the two fractions removed at 4 and 5, as compared with the original charging stock introduced at 1. Where oil of a very highly or wholly paraffinic nature is available without recourse to solvent extraction methods, such oil may be introduced to the line 4 through a line 6 having a pump 7 while oil from any outside source which is substantially free from paraffinic constituents or, in any event, is very highly concentrated in non-paraffinic constituents may be introduced to the line 5 through a line 8 having a pump 9. By means of a pump 11 located in the line 4, paraffinic oil is delivered to a furnace 12 which may be of any desired form of construction but will ordinarily comprise what is generally known in the art as a tube still and wherein the oil is heated to an elevated temperature and pressure effective to promote conversion in the presence of olefinic gas. Such olefinic gas may be added from any suitable outside source through a line 13 having a pump or compressor 14 or by means of a line 15, a line 16 or a line 17. The source of the gases introduced through the lines 15, 16 and 17 or any of them will be set forth more clearly hereinbelow.

Within the furnace 12 the paraffinic oil and the olefinic gas are reacted under suitable conversion conditions which, in the absence of the catalyst or in instances where catalytic effect is secondary, may comprise temperatures of 700° to 1,000° F. and pressures of from 500 to 3,000 lbs. per sq. in., the time of contact being relatively long and, in any event, adequate to carry the reactions to the desired extent. With catalysts of a more highly active nature, such as sodium aluminum chloride, and catalysts of the general type of adsorbent clays, such as fuller's earth

and the like, somewhat lower temperatures of 500° to 700° F. and pressures of 300 to 1,000 lbs. per sq. in. may be suitable, while, with still more active catalysts, such as phosphoric acid, aluminum chloride and boron fluoride, still lower temperatures and pressures of, for example, from 100° to 500° F. and 100 to 500 lbs. per sq. in., may be employed and activators, such as hydrochloric acid and water vapor, may sometimes be employed to good effect. It will be understood, however, that while we have given the above temperature and pressure ranges as being those which we believe to be more suitable, it is contemplated that our variations therefrom may be resorted to under individual conditions of operation and charging stocks.

After conversion, the highly heated products pass from the furnace 12 to a transfer line 20 wherein may be located a pressure reducing valve 21 to an evaporator 22 from which residual constituents are withdrawn through a valved line 23 while vaporous products pass through a vapor line 24 to a conventional fractionating tower 25. In passing to the tower 25, the vapors are subjected to fractional condensation for the separation of relatively clean heavy constituents of the nature of gas oil, such gas oil being removed from the bottom of the tower 25 through a valved line 26. The gas oil thus removed at 26 may, if desired, be recycled to the furnace 12 if of a sufficiently paraffinic nature and, if not, may either be discarded from the system or cooled and returned to the solvent extraction unit 3 by means not shown on the drawing for extraction and further utilization in the process.

In any event, the overhead vapors from the tower 25 comprising gasoline and lighter constituents or gases pass through a line 27 to a condenser 28 and thence to a separator 29 which is preferably maintained under a relatively high pressure of, for example, about 200 lbs. per sq. in. and from which fixed gases comprising hydrogen and methane, and in some instances, also ethane and ethylene, may be withdrawn through a valved line 30 and removed from the process while the condensate passes through a line 31 wherein may be located a valve 32 and a pump 33 to a conventional rectifier or stabilizer 34 where the gasoline is fractionated to remove constituents intermediate between the desired gasoline fraction and fixed gases. Stabilized gasoline is withdrawn through a valved line 35 while overhead from the stabilizer 34 passes through a line 36 to a condenser 37 and thence to a pump 38 or compressor 39. The overhead thus withdrawn will contain varying quantities of propane, propylene, butanes and butylenes, and may, if desired, contain some ethane and ethylene.

It will be understood by those skilled in the art that in many cases, especially where the separation of the condensate is accomplished under relatively low pressure, these intermediate gaseous constituents may be withdrawn from the separator 29 together with the fixed gases and, in such instance, the gases withdrawn from the separator 29 will be fractionated in any suitable manner to remove hydrogen and methane and also ethane and ethylene to the extent desired, the object in any event being to separate the light products of cracking into gasoline, a fixed gas fraction comprising largely hydrogen and methane, and an intermediate fraction comprising largely constituents from propylene to butane and it may be assumed that, in any event,

the intermediate fraction is delivered to the pump or compressor 38.

Where desired, this fraction, however recovered, may be recycled to the furnace 12 through the line 17 wherein is located a valve 40. Alternatively, this fraction may be delivered through a line 41 having a valve 42 to another unit to be described hereinbelow for conversion in the presence of non-paraffinic oil, this latter procedure being followed wherever the fraction delivered to the pump 38 is of a highly or wholly paraffinic nature.

As a still further alternative, the fraction delivered to the pump or compressor 38 may be delivered through a line 43 having a valve 44 and thence through line 45 to a gas separation unit 46 wherein the gases are treated for separation of paraffinic and olefinic constituents. Additional hydrocarbon gas from any outside source, such, for example, as natural gas or cracking plant gas, may also be delivered to the gas separation unit 46 through a line 47 having a pump or compressor 48 and a valve 49.

The gas separation unit 46 is so conducted as to separate the gases into a highly paraffinic fraction which is removed through a line 51 and a highly olefinic fraction removed through a line 52 while hydrogen and methane and, where desired, also ethane and ethylene may be removed if present in the gas delivered to the unit 46 through a valved line 53. In general, the gas separation unit 46 will be somewhat similar to the solvent extraction unit 3 and other fractionation or solvent extraction, or both, methods may be employed although it may be observed that where solvents are employed the initial extraction step will ordinarily take place under such pressure as to maintain the gases in the liquid phase. As a suitable solvent for effecting separation between paraffinic and olefinic constituents, we may mention furfural, the boiling point of which is sufficiently high to facilitate separation of the extract from the solvent. Other solvents for the purpose include acetone, a solution of sulphur dioxide in a ketone, and solutions of mercury salts such as mercury sulphate, cuprous chloride and silver nitrate.

The olefinic gases removed from the line 52 are compressed by means of a pump or compressor 53 to the requisite pressure and can then be returned through the line 15 to the furnace 12 for reaction in the manner hereinabove set forth while the paraffinic gas fraction removed at 51 may be delivered by means of a pump or compressor 54 for reaction with non-paraffinic oil as will be set forth hereinbelow.

In reacting the non-paraffinic oil fraction removed at 5 or added to the line 6, essentially the same procedure may be followed as in the instance described hereinabove in which the paraffinic oil fraction is reacted with olefinic gases; thus, this fraction may be delivered by means of a pump 60 and a line 61 to a furnace 62 where it is subjected to elevated temperature and pressure with or without the presence of a catalyst under the conditions already set forth hereinabove with respect to the operation taking place in the furnace 12 and in the presence of a highly paraffinic gas added from any suitable outside source through a line 63 having a pump or compressor 64 or through a line 44 or through a line 65 communicating with the line 51 and pump or compressor 54. Thus the residue gases in the operation taking place in the furnace 12 may

be delivered to the furnace 62 through the line 41 or the paraffinic fraction recovered at 51 may be delivered to the furnace 62 through the line 65 or additional paraffinic gas may be added through the line 63.

In any event, the hot products from the furnace 62 after conversion pass through a transfer line 70 which may be provided with a reducing valve 71 to an evaporator 72 wherein residual oil or tar is removed through a valved line 73 while vapors pass through a line 74 to a fractionating column 75 of conventional construction. Gas oil is removed from the bottom of the fractionating column 75 through a valved line 76 and may be recycled to the furnace 62 or removed from the system or may be cooled and delivered to the solvent extraction unit 3 by means not shown on the drawing as in the case of the gas oil withdrawn through the line 26 from the fractionating column 25.

The overhead vapors from the fractionating column 75 pass through a vapor line 77 to a condenser 78 and thence to a separator 79 from which fixed gases are removed through valved line 80 while condensate passes through a line 81 having a valve 82 and a pump 83 to a rectifier or stabilizer 84. Stabilized gasoline is withdrawn from the stabilizer 84 through a valved line 85 while overhead comprising constituents intermediate between fixed gases and gasoline passes through a line 86 to a condenser 87 and thence to a pump or compressor 88.

As in the previous instance, the fractionation of the various products may be variously accomplished but, in any event, the object is to separate the fractions comprising largely hydrogen and methane, as well as ethane and ethylene, to the desired extent, the gasoline fraction and an intermediate fraction comprising largely propane, propylene, butanes and butylenes, but which may contain some ethane and ethylene, as desired. This fraction, if sufficiently concentrated in olefinic constituents as distinguished from paraffinic constituents, may be delivered from the pump or compressor 88 through the line 16 wherein may be located a valve 89 to the furnace 12 for reaction with the paraffinic oil introduced thereto or alternatively where the concentration of olefins is not so great, this fraction is delivered through a line 90 having a valve 91 and thence through the line 45 to the gas separation unit 46. It will not ordinarily be desired to recycle gas from the compressor 88 directly to the furnace 62.

If desired, the paraffinic fraction delivered to the pump or compressor 88 may first be cracked at high temperatures and preferably low pressures to increase its content of olefins before being delivered to the furnace 12. Thus, temperatures of from 1100° to 1500° F. and pressures of from atmospheric to 200 lbs. per sq. in. are suitable for this purpose. Since this operation is well known as such in the art, no means for this purpose have been specifically illustrated in the drawing, it being understood that in this event the gases would be delivered from the pump 88 to a suitable cracking furnace and thence either with or without cooling and fractionation to remove hydrogen and methane, as desired, and after compression, to the desired extent through the line 15 into the furnace 12.

While we have described our invention hereinabove with respect to various modifications and operative details, it will be understood by those skilled in the art that our invention is not limited to such illustrative examples or details but may

variously be practiced and embodied within the scope of the claims hereinafter made.

We claim:

1. The method of producing low-boiling hydrocarbon oil suitable for use as motor fuel from relatively heavy hydrocarbon oil and normally gaseous hydrocarbons which comprises separating said oil into a highly paraffinic fraction relatively free of non-paraffinic constituents and a non-paraffinic fraction relatively free of paraffinic constituents, subjecting the highly paraffinic fraction together with gases predominating in olefinic constituents substantially free from hydrogen and methane to elevated pressure and temperature effective to promote decomposition of said oil fraction and polymerization of said olefinic gas, fractionating the products to separate and recover materials higher boiling than the desired motor fuel product, normally gaseous hydrocarbons, and a gasoline fraction, separating gases predominating in paraffinic constituents from said normally gaseous hydrocarbons, separately subjecting said non-paraffinic oil fraction together with at least a portion of said gases predominating in paraffinic constituents to elevated temperature and pressure effective to promote reaction between said normally gaseous hydrocarbons and said oil fraction, thereby producing gasoline, and fractionating the products to recover a second gasoline fraction therefrom.
2. The method of producing low-boiling hydrocarbon oil suitable for use as motor fuel from relatively heavy hydrocarbon oil and normally gaseous hydrocarbons which comprises separating said oil into a highly paraffinic fraction relatively free of non-paraffinic constituents and a non-paraffinic fraction relatively free of paraffinic constituents, subjecting the highly paraffinic fraction together with gases predominating in olefinic constituents substantially free from hydrogen and methane in a first conversion zone to elevated pressure and temperature effective to promote decomposition of said oil fraction and polymerization of said olefinic gas, fractionating the products to separate and recover materials higher boiling than the desired motor fuel product, a normally gaseous hydrocarbon fraction, and a gasoline fraction, subjecting the non-paraffinic oil fraction together with gases predominating in paraffinic constituents substantially free from hydrogen and methane in a second conversion zone to elevated temperature and pressure to effect conversion thereof to products including gasoline, fractionating the products to separate and recover materials higher boiling than the desired motor fuel product, a second normally gaseous hydrocarbon fraction, and a second gasoline fraction, combining said normally gaseous hydrocarbon fractions and recovering therefrom gaseous fractions predominating, respectively, in olefinic and paraffinic

constituents and relatively free of hydrogen and methane, and returning said last-mentioned fractions to said first and second conversion zones, respectively.

3. The method of producing low-boiling hydrocarbon oil suitable for use as motor fuel from relatively heavy hydrocarbon oil and normally gaseous hydrocarbons which comprises separating said oil into a highly paraffinic fraction relatively free of non-paraffinic constituents and a non-paraffinic fraction relatively free of paraffinic constituents, separating said gaseous hydrocarbons into a fraction predominating in olefinic constituents and a fraction predominating in paraffinic constituents, subjecting the relatively high paraffinic oil fraction together with said gas fraction predominating in olefins to elevated pressure and temperature effective to promote decomposition of said oil fraction and polymerization of said olefinic gas, separately subjecting said non-paraffinic oil fraction together with said gas fraction predominating in paraffins to elevated temperature and pressure to effect decomposition of said oil fraction and conversion of said gas fraction, separately fractionating the products from each conversion operation to separately recover gasoline therefrom and normally gaseous hydrocarbons, fractionating the gaseous hydrocarbons to recover a fraction predominating in olefins and a fraction predominating in paraffins, and returning said last-mentioned fractions to said first and second conversion zones, respectively.

4. The method of producing low-boiling hydrocarbon oil suitable for use as motor fuel which comprises subjecting a highly paraffinic oil relatively free of non-paraffinic constituents together with gases predominating in olefinic constituents and substantially free from hydrogen and methane in a first conversion zone to elevated pressure and temperature effective to promote decomposition of said oil and polymerization of said olefinic constituents, simultaneously and separately subjecting a non-paraffinic oil relatively free of paraffinic constituents together with gases predominating in paraffinic constituents in a second conversion zone to elevated temperature and pressure to effect conversion thereof to products including gasoline, fractionating the products from said conversion zones to recover materials higher boiling than the desired motor fuel product, a gasoline fraction and normally gaseous hydrocarbons, recovering from normally gaseous hydrocarbons thus obtained gaseous fractions predominating respectively in olefinic and paraffinic constituents and relatively free of hydrogen and methane and returning said last-mentioned fractions to said first and second conversion zones, respectively.

HAROLD V. ATWELL.

MALVIN R. MANDELBAUM.
